UNITED STATES PATENT OFFICE

JOHN CAVANAGH, OF SOUTH NORWALK, CONNECTICUT, ASSIGNOR TO THE CROFUT & KNAPP COMPANY, OF SOUTH NORWALK, CONNECTICUT, A CORPORATION OF CONNECTICUT

HAT

Application filed July 26, 1929. Serial No. 381,325.

This invention relates to hats and is applicable to both stiff and soft hats having a reinforced finished edge made by felting fur or fibre.

5 The present invention is an improvement on my previous hat Patent No. 1,053,973, dated February 25, 1913, and is designed to produce a more desirable hat in that the reinforced welted felt edge is superior to that 10 described in the said patent, because the brim will hold in place much longer than a welt edge made in accordance with the disclosure of that patent and all other hat brims with which I am familiar.

15 The object of my invention is to provide a relatively light weight hat with an improved form of reinforced edge produced by an improved process that includes the application of an additional piece or pieces of felt applied in a certain specific manner.

With these and other objects in view, the invention resides and consists in the construction and novel combination and arrangement of parts hereinafter more fully 25 described, illustrated in the accompanying drawings, and pointed out in the claims here-to appended, it being understood that various changes in the form, proportion, size, and minor details of construction within the 30 scope of the claims may be resorted to without departure from the spirit, or sacrificing any of the advantages of the invention.

Similar characters of reference denote like or corresponding parts throughout the several figures of the accompanying drawings forming a part of this specification and upon which

Fig. 1 is a perspective elevational view of a hat body which has been partially shrunk 40 to illustrate the method of applying a specific form of felt strip in the edge of the brim portion;

Fig. 2 is a vertical sectional view as taken on line 2 of Fig. 1 showing the inserted strip 45 and folded edge;

Fig. 3 is a similar sectional view showing a modified reinforced roll edge with strip inclosed;

Fig. 4 shows a further like section illustrating a different application of a specially

formed strip in accordance with my invention;

Fig. 5 shows a vertical sectional view through a finished hat brim with reinforced edge constructed in accordance with my invention; and

Fig. 6 shows perspective view of a soft style of trimmed hat having a reinforced edge portion formed in accordance with the disclosure of my invention.

Hats of this kind are usually made of fur and according to present day methods are formed into a hat body in a fur forming machine wherein given quantities of fur are blown on a perforated metal cone to which it adheres by reason of a suction of air there-through, to the extent that a conical shaped fur hat body is formed of substantially uniform thickness. The hat bodies are then saturated with hot water which causes the 70 fibres of the fur to adhere and shrink sufficient so that the body may be removed from the cone, whereupon a number of the bodies are laid, one upon the other, forming a bundle which is folded, dipped into scalding water, taken out and rolled for the purpose of further shrinking the bodies. This process is known as sizing or felting and by continuing the operations as suggested, 75 serves to reduce the body to the desired 80 sizes for stiffening, blocking and finishing. In the course of this sizing operation the short fibres of fur while more or less disposed in a crisscross manner, yet are mostly disposed in the body in a given direction, especially 85 throughout its brim portion.

In the drawings, 10 represents a felted hat body which has been partly sized, 11 the brim portion and 12 the rolled annular edge. 13 indicates a narrow strip of felt which is applied in the brim portion of the body and as shown is inclosed by the edge portion of the brim which is turned over on the strip and upon the brim in a way to inclose the strip. This turned over edge portion is 90 sewed down with a coarse line of stitches 14 to temporarily hold it in place during the further sizing operations of the hat body. The edge may obviously be turned over as shown in Figs. 1 and 2 and in case a heavier 95

edge of the brim is desired, the stock may be rolled as shown in Fig. 3 thus providing an increased thickness of material. In Fig. 4 the edge is shown to be reinforced by a 5 slightly wider strip that is U-shaped in cross section and is applied like a binding. Each of these forms of reinforcing strip would employ the temporary stitching above suggested.

10 The invention resides more particularly in providing a reinforcing strip of felt whose grain is disposed at a right angle or substantially so, to that of the body of the hat so that further felting operations of the body 15 will felt the strip into the body in a cross-wise manner, the purpose being to obtain greater strength in the edge of brim. The principle involved being like that employed in the use of several thicknesses of wood 20 veneer except that in this case, the felting operation is employed to bind the layers of material together. These cross grained strips or strands of felt may be impregnated with insoluble shellac or any insoluble stiffening 25 or treated with various chemicals so as to toughen them. By combining physical strength as in crosswise grained felt and adding to it a stiffening such as shellac or leatherized strip, which is then felted into the 30 folded edge, a very tough edge may be obtained which will not differ in appearance materially from the ordinary welted felt edge, yet has the advantage of holding the brim longer than heretofore.

35 Having thus described my invention, what I claim and desire to secure by Letters Patent is:

1. A felt hat brim having a reinforced edge portion, said reinforcing comprising 40 a layer of felt felted into and crosswise of the grain of the hat brim.
2. A felt hat brim having a reinforced edge portion including an applied strip of felt or any potential felting material whose 45 grain is disposed at approximately right angles to that of the brim, the said thicknesses being felted together.

Signed at South Norwalk, in the county of Fairfield and State of Connecticut, this 50 22nd day of July, A. D. 1929.

JOHN CAVANAGH.
